FLEXIBLE BAND, CHAIN, OR LINKAGE

Application filed December 27, 1928. Serial No. 328,761.

This invention relates to an improved construction of flexible bands, chains or linkages for use in the manufacture of articles of jewelry such as bracelets, wrist watch straps, 5 necklaces, girdles or the like.

One object of the invention is to provide a flexible band, chain or linkage comprising a series of articulated link-elements which are flexibly connected to adapt the article 10 to conform to the contour of the surface on which it is worn.

Another object of the invention is to provide a device of the type specified wherein the articulated link-elements are connected 15 by means substantially enclosed therein so that all mechanical parts are entirely covered and concealed from view.

Another object of the invention is to provide a device of the type specified wherein 20 the articulated link-elements are connected by means which require no pins, rivets, screws or the like, and which is also devoid of any soldered joints.

Another object of the invention is to provide a device of the type specified which may 25 be constructed from sheet-metal parts struck up in dies and capable of being rapidly assembled without particular skill or expertise on the part of the workman and without the use of tools.

Another object of the invention is to provide a device of the type specified wherein the connecting means for the link-elements 30 are merely inserted in place to be automatically interengaged and interlocked to permanently hold the parts in coupled relation.

Another object of the invention is to provide a device of the type specified wherein the connecting-members for the link-elements 35 are adapted to interlock with a snap action when inserted into the links and their interlocking portions are disengageable by forcibly drawing the members outwardly from the links whereby the parts may be assembled or disassembled without permanent deformation thereof.

Another object of the invention is to provide a device of the type specified which may 40 be manufactured at low cost while at the

same time furnishing a stronger and more durable structure.

Further objects of the improvement are set forth in the following specification which describes several preferred forms of construction of the invention as illustrated by the accompanying drawings. In the drawings: 55

Fig. 1 is a perspective view showing the invention as embodied in a flexible band, chain or linkage adapted for various uses; 60

Fig. 2 is a plan view of a portion of the band or linkage showing the link-elements partly in section at one end of the band to illustrate the interlocked connecting-members and the method of inserting them into 65 the links;

Fig. 3 is an edge view of a section of the band or linkage showing it as somewhat enlarged over Fig. 2;

Fig. 4 is an enlarged perspective view showing one form of the complementary connecting-members for the link-elements; 70

Fig. 5 is a view similar to Fig. 2 showing a modified form of construction of the link-elements and connecting-members; 75

Fig. 6 is a perspective view of the connecting-members illustrated in Fig. 5;

Fig. 7 is a perspective view of the main link-element as employed in the construction shown in Fig. 5; and 80

Fig. 8 is a detailed view of a still further modified form of connecting-members for the link-elements.

The present invention relates in general to a novel and improved construction of connecting-means for joining the link-elements of flexible bands, chains and linkages, and also contemplates an improved method of assembling the parts to provide for permanency of 85 their connection or joinder. As herein shown the completed article constitutes a band, chain or linkage which is adapted to be used as a strap or bracelet for wrist watches in accordance with a prevailing style or custom, but it may be adapted for other purposes, for instance, in the manufacture of necklaces, arm-bands, anklets, girdles, watch-fobs, watch-guards, and similar articles of jewelry and adornment. 90

As herein shown the linkage is of the flat 100

band type, composed of a series of relatively narrow, hollow link-elements 2 extending transversely of the band and closely coupled in articulated relation. The link-elements 5 2 may be of any other suitable outline and contour, however; for instance, they may be of more or less circular shape instead of rectangular in cross-section. As illustrated more particularly in Figs. 2 and 3, the link-elements 10 2 are cut from lengths of tubular stock as commonly used in the jewelry manufacturing art, being in the form of open-ended boxes having a flat top 3, a corresponding bottom 4 and narrower flat sides 5.

15 In the embodiment of the invention as illustrated in Figs. 1 to 3 of the drawings, the connecting-means for the tubular link-elements 20 2 are constructed in the form of bifurcated members 6 and 7 of substantially hair-pin shape. The members 6 and 7 may 25 be struck up in dies from flat sheet-metal stock, being formed with their opposite legs notched in complementary fashion to adapt them to be sprung into interlocking engagement when they are inserted into the ends of adjoining link-elements 2 in straddled relation with respect to the sides thereof as shown in Fig. 2. One connecting-member 6 has its 30 opposite legs 8 generally tapered toward the end on the outside and notched at 9 to provide detent shoulders. The complementary connecting-member 7 has its legs 11 tapered toward the ends on their inside edges and notched at 12. It is to be noted that the 35 detent shoulders of the notches 9 and 12 on both connecting-members 6 and 7 are inclined inwardly away from the tips of the legs 8 and 11. That is to say, the detent shoulders of the notches instead of being perpendicular to the longitudinal axis of said members are inclined at an angle thereto, see Figs. 2 and 4, whereby the detent shoulders may be disengaged by forcibly pulling the members 6 and 7 to permit them to be withdrawn from the 40 ends of the link elements. By this form of construction provision is made for disassembling the links of the band or bracelet so that one or more links may be removed to shorten the band or extra links inserted to 45 increase its length. Each element 6 and 7 is widened at the end with a sort of head-piece 14 projecting outwardly from the sides of their legs to provide portions 15 which abut similar portions on the next pair of connecting-members 6 and 7 assembled in the linkage as illustrated in Fig. 2. In this way the abutting sides of the heads 14 of the adjacent pairs of connecting-members 6 and 7 form an unbroken surface along the marginal edges of the band or linkage as shown in Fig. 1, while their legs are spaced away from the adjacent legs of the next connecting-member. 50

55 In assembling the parts of the device to form the band, chain or linkage, the tubular link-elements 2 are arranged side by side in

series and the connecting-members 6 and 7 inserted into their open ends as illustrated at the right in Fig. 2. One member 6 is inserted at one side of the linkage with its arms 8 straddling the adjacent side walls 5 70 of two adjoining link-elements 2, and the other member 7 is inserted in the same manner at the opposite side of the linkage. Pressure is then exerted on the ends or head-pieces 14 of the two members 6 and 7 to force them 75 together to interlock their notched ends. That is to say, as the two members 6 and 7 are pushed into the hollow links 2 the tapered, notched ends of the legs 8 on the member 6 will slide in between the legs 11 of the member 7, thereby forcing the legs 11 to spring apart until the notches 9 interengage with the notched portions 12 of the element 7. The inherent resiliency or spring tendency 80 of the legs of the bifurcated member 7 causes them to snap back into place to form a close joinder with the notched legs of the member 6, as clearly illustrated in Fig. 2 of the drawings. It will be observed from Fig. 3 that the connecting-members 6 and 7 are of a thickness corresponding substantially with the space between the top 3 and bottom 4 of the tubular link-elements 2 and, consequently, when the two interlocked elements are 85 enclosed within the links they will be prevented 90 from lateral displacement. That is to say, one member cannot be lifted or canted out of engagement with the other member to cause their legs to become unlocked. On the other hand, the interlocked connecting-members 6 and 7 may be disengaged by seizing their heads 14 projecting along the sides of the bracelet and forcibly drawing them apart to cause their detent shoulders to ride outwardly one over the other. 95

100 In this way any one or more links may be removed from the band, chain or linkage to shorten its length or, in other cases, extra links may be inserted to increase its length 105 as before mentioned. The disconnection of the links in the manner explained may be accomplished by the jeweler or by the wearer himself when it is necessary to alter the length of the bracelet to fit the wrist. 110

115 Figs. 5, 6 and 7 of the drawings illustrate another embodiment of the invention in which the bifurcated connecting-members 16 and 17 are of somewhat different construction and the tubular link-elements 20 are also 120 of slightly different form. As shown more particularly in Fig. 7, the tubular link-element 20 has its sides 25 cut away at the ends to form recesses 26 between the top 23 and bottom 24 of the link. These recesses 26 receive the end-portions of the connecting-members, and this form of box-link may be used with the construction shown in Figs. 2 and 4 so that the heads or end-pieces 14 of the connecting-members 6 and 7 will be received 125 130

within and their edges arranged flush with the ends of the links.

In the construction shown in Fig. 6, the two complementary connecting-members 16 and 17 are formed from relatively thin sheet-metal stock and folded to provide end-portions 18 with opposite overlying bifurcated portions 30 and 31 extending forwardly therefrom. It will be observed that the two connecting-members 16 and 17 are of exactly the same construction, one member being reversed in position in relation to the other to provide for the interengagement of their interlocking parts. Each member has a pair of relatively long legs 32 extending from the folded portion 31, with the ends of these legs crimped or bent at 33 to form zig-zag portions of opposite angles. The other folded portion 30 of each member is cut away to form shorter legs 34 which are bent or crimped at 35 to form zig-zag portions adapted to interlock with the bent ends 33 of the opposite connecting-member.

Referring to Fig. 5 of the drawings, it will be understood that the members 16 and 17 are inserted into the opposite ends of the tubular link-elements 20 in the same manner as in assembling the parts of the chain or linkage illustrated in Fig. 2. As the members 16 and 17 are forced toward each other with their legs 34 and 32 straddling the recessed side walls 25 of two abutting link-elements 20 the crimped ends 35 of the short legs 34 on one member will spring over and interlock with the bent end portions 33 of the long legs 32. As the opposite crimped legs of the two members 16 and 17 are thus sprung into interlocking engagement the end-portions 18 of the members are received within the ends of the tubular links 20, the recesses 26 accommodating that portion of the stock which joins the ends of the legs of the members.

Fig. 8 illustrates a still further modification in the form of construction of the connecting-members for the links in which a tubular bifurcated member 36 is provided with split end-portions adapted to receive the ball-like ends of the legs of a similarly-shaped member 37. The member 36 may be constructed of tubular stock such as hollow drawn wire bent into substantially U-shape. The ends of its legs 38 are swaged inwardly at 39 and split longitudinally on opposite sides at 40. The member 37 may be formed of solid wire bent into U-shape with the ends of its legs 41 rounded at 42 and notched or grooved at 43. These two members 36 and 37 may be employed to assemble links of the form shown in Fig. 7, the legs of the bifurcated members being entered into the ends of the tubular link-elements 20 and pushed into place to cause the inturned rims 39 of the hollow legs 38 of the member 36 to snap into the grooves 43 at the ends of the legs 41 on the member 37. In this way a secure

and substantially permanent lock is effected between the two connecting-members for holding the link-elements in articulated relation.

It will be observed from the foregoing that the present invention provides a particularly simple and efficient connecting-means for joining a series of hollow or tubular links in articulated relation so that the whole band, chain or linkage is adapted for flexure. As before noted, the main link-elements may be cut from a length of hollow tubular stock which is manufactured and merchandised in various forms, and the connecting-members may be stamped out from sheet-metal at a rapid rate of production and at very economical cost.

In some cases the main link-elements may be of solid construction with tubular end-portions for receiving the connecting-members, or they may be of such form as to provide a setting for gems or brilliants.

In assembling the parts of the band, chain or linkage it is only necessary to bring the tubular or hollow links into close association and then insert the connecting-members into their ends to cause them to interlock in permanently fixed relation. As a result of this form of construction and the method of assembling the parts a particularly neat and well-finished article is produced with the joints between the connecting-members entirely enclosed and concealed from view. The interlocked legs of the opposite connecting-members hold the links in close association while adapting them to rock or cant one on another to provide for flexure of the articulated structure, and the parts are permanently joined together without pivot-pins, rivets, studs, screws or like added elements. It will also be noted that there are no soldered joints between the parts and no hand work such as bending with pliers or other tools is required in assembling the pieces.

The improved structure is particularly strong and rugged, the interlocking legs of the connecting-members tending to reinforce each other, so that the whole chain or linkage is practically proof against breakage or dislocation of its parts. The finished article is also more artistic in appearance than similar devices having soldered or riveted joints, or interlocking parts which are exposed to view, and is thus adapted for use in the manufacture of high class jewelry.

It has been observed that the form of the link-elements may be changed without reference to the structure and arrangement of the connecting-members and it has also been shown that the connecting-members may be of different forms of construction to interlock to couple or join the parts of the linkage in articulated relation. Various other modifications may be made in the form and construction of the parts of the device with

out departing from the spirit or scope of the invention, and therefore, without limiting myself in this respect, I claim:

1. A jointed band in which is comprised a pair of flat tubing lengths joined by a pair of coacting U-shaped elements each having one arm extending into one tubing length from one end thereof to partially lap past the arm extending into the same tubing length from the opposite end thereof, the two arms being confined by the tubing against relative movement in the direction of its narrower dimension but having clearance for relative movement in its wider direction, the arms of one U-shaped element terminating in hooks adapted to snap-lock with the arms of the other element when the interengaging arm ends are forced past each other into locking position.
2. A flexible bracelet comprising a plurality of tubular links, and staples having their legs received within opposite ends of adjacent links for interconnecting said links, the legs of opposite staples having mutually interfitting portions engaging with a snap action when said staples are pressed together separably to interlock the staples, whereby the parts may be assembled or disassembled without permanent deformation thereof.
3. A flexible bracelet comprising a plurality of tubular links, and staples having their legs received within opposite ends of adjacent links for interconnecting said links, the corresponding legs of opposite staples having mutually interfitting cam portions engaging with a snap action when said staples are pressed together separably to interlock the staples, whereby the parts may be assembled or disassembled without permanent deformation thereof, the interlocking connection between said opposite pairs of staples being independent of other staples.
4. A flexible bracelet comprising a plurality of tubular links, and staples having their legs received within opposite ends of adjacent links for interconnecting said links, the legs of opposite staples having inclined surfaces on their opposite sides mutually engageable when the legs of one staple are sprung over the legs of the opposite staple to interlock said staples, and mutually separable when the staples are pulled apart, whereby the parts may be assembled and disassembled without permanent deformation thereof.
5. In an article of the class described, a pair of parallel tubes, a pair of staples having their legs received within opposite ends of said tubes, the legs of one staple overlapping the ends of the other staple, and complementary notches and grooves on the contiguous surfaces of the respective overlapped legs for separably interlocking the staples, said notches and grooves having in-

clined surfaces engageable with a snap action when the staples are sprung together and separable from each other when the staples are pulled apart, whereby the parts may be assembled and disassembled without permanent deformation thereof.

6. In a band, chain or linkage, the combination of a plurality of hollow link-elements, means for connecting said link-elements in articulated relationship comprising bifurcated members adapted for insertion into adjoining links in straddled relation with the walls thereof, and interlocking means engageable by snap action for securing said bifurcated members in connection, said interlocking means being formed to provide for the release of the members by forcibly drawing them apart whereby the link-elements may be assembled and disassembled without permanent deformation of the parts.

7. A flexible bracelet comprising a plurality of link-elements having hollow portions, staples having their legs received within opposite ends of adjacent links for interconnecting said links, and mutually interfitting means engaging with a snap action when said staples are forced into the links to hold the staples in place to connect the links in articulated relationship, said interlocking means being shaped to effect their disengagement when the staples are forcibly pulled apart whereby the parts of the bracelet may be assembled or disassembled without permanent deformation thereof.

In testimony whereof I affix my signature.

CHARLES H. KESTENMAN.
